UNITED STATES PATENT OFFICE.

LESTER L. LADD, OF LOCKPORT, ILLINOIS.

GRAIN-SORTING DEVICE.

Application filed August 2, 1923. Serial No. 655,255.

My invention relates to grading apparatus and more particularly to a grain grader which is adapted to separate heavier and lighter grains from each other.

In connection with milling, it is often desirable to separate lighter grains or particles from heavier grains or particles. This is particularly desirable in connection with the milling of grains that are hulled in the process of milling, in order to insure the separation of any grains still having hulls thereon from the hulled grain, as the presence of hulls even in small quantities will interfere seriously with the quality of the product produced. This is particularly true in the making of rolled oats in which the hulls, if any are present, cause unpalatable particles to be present in the finished product.

Apparatus has been in use for accomplishing this separation which is very bulky, this apparatus operating on the principle of a shaker having a reciprocating movement which, due to the construction of the passageways for the grain on the shaker table, causes the grains with the hulls thereon to travel in one direction and the hulled grains in the opposite direction. This apparatus, while fairly successful, is very bulky and causes a very great amount of vibration in the building in which it is located. The capacity is small and the separation is not absolutely perfect at all times.

It is the purpose of my invention to provide a grain grading apparatus which will separate the grain into a group of lighter particles and a group of heavier particles which is compact and highly efficient and which causes a complete separation of the particles or grains into the groups.

It is the further purpose of the invention to provide a device of the above mentioned character which is of large capacity for the size thereof and which is so constructed that the separating elements can be arranged in stack formation or in tiers.

It is still a further purpose of the invention to provide a device of the above mentioned character in which only a small amount of movement of the separating elements is necessary to separate the grain into the groups mentioned above and in which the vibration, caused to the building by the operation of the device, is greatly reduced.

The separating elements preferably have a rapid rotary motion of small radius and

these are inclined preferably in two different directions although it may be only necessary to incline the same in one direction. The grain is preferably fed on the elements at one end thereof and travels, due to the construction of the elements and due to the motion thereof, in streams which gradually separate into two well defined streams at the opposite end of said device from which the grain is fed on the same, one of the streams being made up of the heavier particles or grains and the other of the lighter particles or grains.

It is still a further purpose of the invention to provide a grain grading apparatus that is made up of separating elements having a rapid rotary motion of small radius, which elements are provided with zig zag shoulders thereon so arranged as to tend to move the grain engaging said shoulders toward one corner of the device, due to the rotation thereof, said element being inclined so that the particles or grains that do not engage the shoulders will move toward the other corner of said device at the end thereof, opposite the end from which the grain is fed on the separating device.

It is another purpose of the invention to provide means for adjusting the separation on the separating elements and means for receiving the separated particles or grains, which is provided with means for adjusting the portions of the separating elements from which particles are discharged into said receiving devices.

Other objects and advantages of the invention will appear as the description of the accompanying drawings proceeds. However, I desire to have it distinctly understood that I do not intend to limit myself to the exact details shown or described, but that I intend to include as part of my invention all such obvious changes and modifications of parts as would occur to a person skilled in this art and as would fall within the scope of the claims.

In the drawings:

Fig. 1 is a side elevation of my improved grain sorting machine, a portion thereof being broken away to more clearly show the discharge end of the machine;

Fig. 2 is a top plan view thereof, partly broken away, as viewed from the plane 2-2 of Fig. 1, portions thereof being in section;

Fig. 3 is an end elevation of the machine

partly in section, as viewed from the grain receiving end thereof;

Fig. 4 is a fragmentary end elevation of the opposite end of the machine;

5 Fig. 5 is a fragmentary perspective view of one of the separating elements; and

Fig. 6 is a fragmentary top plan view thereof.

Referring in detail to the drawings, the 10 machine comprises a base 10 upon which are mounted the vertically extending members 11 of the machine framework. The members 11 are connected together at the upper ends thereof by means of the longitudinally 15 extending frame members 12 and the transversely extending end members 13 of the framework. Extending between the longitudinally extending members 12, are the cross members 14 upon which is mounted 20 the motor 15 which is provided with a pulley 16 over which the belt 17 operates. Mounted on said longitudinally extending members 12, are the castings 18 which are made in the form of brackets, said brackets 18 being secured in any suitable manner to the member 12 and each having an upwardly extending flange 19 and a clamping member 20 which clamps the rods 21 thereto, said clamping member 20 being held in clamping 25 position by means of the bolts 22. The rods 21, as will be seen from Figs. 2, 3 and 4, are arranged in pairs and depend from the brackets 18, there being four of said brackets. Clamped to the lower ends of said 30 rods 21 are the longitudinally extending members 23 of the framework which will be described in detail below. Said members 23 are provided with wings 24 extending laterally therefrom, said wings being provided 35 with socket portions 25 for receiving the rods 21. Co-operating with said wings 24 are the clamping members 26 which are provided with similar socket portions 27. The clamping members 26 are clamped to the 40 wings 24 by means of the bolts 28. The wings 24 are reinforced by means of the reinforcing members 29. The framework, of which the members 23 are a part, further comprises a cross member 30 which is provided 45 with a pair of vertically extending end portions 31 that are bolted by means of the bolts 32 to said members 23 substantially midway thereof. It will be noted that the framework, comprising the members 23 and 50 31, is hung from the rods 21 which are resilient, thus permitting of a certain amount of movement of said framework, comprising members 23 and 31, relative to the main framework of the machine.

55 The transverse member 30 is provided with a reinforcing web 33 which is formed into a bracket member 34 having a bearing 35 serving as a bearing for the shafts 36 carrying a pair of idler pulleys 37. The transverse member 30 is bifurcated intermediate

the ends thereof, providing an upper transverse member 38 and a lower transverse member 39. The member 38 is provided with a bearing 40 and the member 39 with a bearing 41 through which the ends of the shaft 42, carrying the flanged pulley 43, extend. Operating over the pulley 16 of the motor 15 and over the pulleys 37 and 43, is the belt 17 which accordingly drives the pulley 43 from said motor 15, and as the motor operates at a very high speed, the pulley 43 will rotate rapidly. Mounted on the shaft 42, to rotate therewith, is the member 44 which is provided with a counter-weight or overbalancing weight 45 made in the form of a segment, as clearly shown in Fig. 2. It will be seen that as the pulley 43 rotates the shaft 42 rapidly and the weight 45 revolves with said shaft, the framework suspended from the rods 21 will be given a rotary movement which is substantially that of a circular pendulum motion of very small radius, this being due to the action of the centrifugal force produced by the rotation of the weight 45 about the axis of the shaft 42, the rods 21, being resilient, permit a certain amount of swinging of the framework out of its normal position, due to the action of said rotating weighted member.

55 Mounted between the side members 23 are the vertically extending partitions or side walls 46 and mounted between said side walls 46 are the shelves 47, said shelves 47, as will be clear from Fig. 3, being inclined from one of the side walls 46 to the other side wall 46. Said shelves 47 may be also inclined somewhat lengthwise thereof, the inclination lengthwise of the machine, if any, thereof being dependent upon the speed with which the grain should travel toward the discharge end of the apparatus to get the desired results. The shelf-like members 47 are shown more in detail in Fig. 5, said members being provided with a surface having zig-zag shoulders thereon comprising the short wall portions 48, extending at an oblique angle to the transverse of said member 47, and the long wall portions 49, extending at an oblique angle to the length of the member 47. The wall portions 48 and 49 alternate lengthwise of the member 47 to provide a zig-zag shoulder thereon, comprising short obliquely extending portions and long obliquely extending portions which alternate with each other. From the shoulders 48 and 49, the surface 50 of the member 47 is inclined downwardly to the next zig-zag shoulder formation which is the same as the one just described. The entire surface of the plate is made up of the inclined upper faces 50 and the obliquely extending shoulders 48 and 49, thus forming a plurality of zig-zag obliquely extending shoulders arranged in substantially parallel relationship to each other.

Mounted between the longitudinally extending members 12, is a feeding device 51 which is of any well known type and which is driven from the pulley 52 mounted on the shaft 53 through the gears 54 and 55. Said feeding device 51 feeds grain, upon rotation of the pulley 52, into the tapering spouts 56 which open into the downwardly inclined spouts 57 opening into the feed boxes 58, 59 and 60 respectively, the feed box 58 being provided on the upper shelf 47, the feed box 59 on the intermediate shelf 47 and the feed box 60 on the lower shelf 47. Only three shelves are shown but it is understood that any number of feed spouts 57 and shelves 47 that may be desired can be provided by merely duplicating the parts shown. The member 58 is provided with side walls 61, and rear walls 62 and is open on the other side thereof and on the top thereof, thus providing an open ended, open topped receptacle opening toward the upper shelf-like member 47. The box 59 is similarly constructed as will be clearly seen from Figs. 3 and 4 and feeds onto the intermediate shelf 47 from the open end thereof, while the box 60 feeds onto the bottom shelf 47 in a similar manner and is similarly constructed. It is, of course, understood that the boxes 58, 59 and 60 move with the shelves 47 and the frame mounted on the rods 21, while the feed spouts 57 are stationary. However, the rotary movement of the movable frame and the parts carried thereby is of such small radius that by providing an open top in the receptacle, sufficient play is allowed for movement of the box-like members relative to the spouts without the spouts interfering in any way with the operation of the device. The direction of rotation and the radius of the path of rotation is indicated by the curved arrow 63 in Fig. 6, and the radius of curvature of the arrow 63 is substantially the radius of the rotary pendulum motion of said plates 47. While the plates 47 have such a pendulum motion, yet this motion is substantially in a plane, due to the fact that the radius of the movement is very small and that the large shelf-like members are mounted on rods of substantially fixed length. It will be noted, upon reference to Figs. 2, 5 and 6, that if a particle of grain 64 moves onto any one of the members 47 and engages with the shoulders 48 and 49, the rotary oscillating movement of the shelf-like member 47 will cause the shoulders 48 and 49 to engage with the grain 64 to move the same toward the left in Fig. 1 and toward the left and top in Fig. 2, toward the right in Fig. 3 and toward the left in Fig. 4. That is, the movement will be toward the higher sides of the plates or shelves 47 and toward the discharge end of said plates or shelves 47, the resultant movement being substantially on a diagonal, as

indicated by the arrow 65 in Fig. 5. In other words, the grain 64, engaged by the shoulders 48 and 49 of the plates, due to the rotative movement of said plates or shelves, will cause a movement of the grains 64 in a general direction toward the corner 66 of the shelves 47, as indicated clearly in Fig. 2. If the feeding boxes 58, 59 and 60 are filled with a mixture of grain comprising heavier and lighter grains or particles, the heavier grains or particles will settle to the bottom of the mass on the oscillating plates or shelves 47 and only the heavier particles will engage with the shoulders 48 and 49 toward the higher side of the shelves, while the lighter particles or grains will float on top of the mixture, and due to the inclination of the shelves or plates 47 downwardly toward the side member 46, shown toward the left in Fig. 3, toward the right in Fig. 4 and toward the bottom in Fig. 2, they will be gradually carried toward the corner at the discharge end of the shelves 47 opposite the corner 66, the shoulders 48 aiding in the movement of the lighter particles toward the discharge end of the shelf and the inclination of the members 47 also aiding in such movement if this is necessary. Said lighter grains or particles are indicated by the numeral 67 in Fig. 2 and it will be seen that the resultant action of the inclination and oscillation of the shelves 47 is that the heavier particles or grains 64 will flow in a stream toward the corner 66 and the lighter particles or grains 67 will flow in a similar stream toward the opposite corner, at the discharge end of the device, from the corner 66, thus entirely separating the particles or grains 64 from the grains or particles 67, there being a space 68 devoid of any grains or particles between the streams of particles 64 and 67, the space gradually widening toward the discharge end of the machine as shown in Fig. 2. It is well known that hulled grains are heavier than unhulled grains and, accordingly, the machine can be used for thoroughly separating hulled from unhulled oats, for example, the grains 64 representing the hulled oats and the grains 67 representing the unhulled or lighter oats. Also, the machine can be used at the same time for separating any chaff or other particles that may be present in the grain as these particles will flow along with the particles 67 having the hulls thereon. A transverse member 69 is provided between the side walls 23 at the discharge end of the device and on said member 69 is mounted a pair of brackets 70 and 71. The bracket 70 supports the hopper 72 and the bracket 71 supports the hopper 73. Said hoppers 72 and 73 are arranged side by side and have inclined side walls, as clearly shown in Fig. 4. Below said hoppers 72 and 73 are provided hoppers 74 and 75 which are

mounted in any suitable manner on the base of the machine and which form the receiving end of ducts or spouts leading to any suitable container or receptacle for the separated grain or to any suitable machines for operating on the separated grain. The member 69 also has a bracket 76 thereon which is provided with a boss 77 for receiving the shaft 78 upon which is mounted the tubular member 79 having a vane 80 extending outwardly therefrom, the member 79 being free to rotate on the shaft 78. Mounted on the outer end of the shaft 78 and clamped in position thereon, by means of the nut 81, is an arm 82 having a segment 83 on the outer end thereon, said segment 83 being provided with a segmental slot 84 through which the pin 85 on the vane 80 extends, said pin being threaded and being provided with a wing nut 86 on the end thereof. The vane 80 is located below and extends beyond the ends of the shelf-like members 47 so that the grain falling off of said shelves at the discharge end thereof will fall either on one side or the other side of said vane. As the relative proportion of grain of the two different characters will vary in accordance with the kind of grain acted upon, and the adjustment of the machine, it is necessary to sometimes vary the angle of the member 80 to vary the proportions of the shelves 47 that lie to the right and left thereon, as viewed from Fig. 4. Thus, of the hulled grain spreads over a larger area, it is necessary to move the vane 80 further toward the right than the position shown in Fig. 4, whereas, if the proportion of hulled grain at the discharge end of the device is such that it spreads over a lesser area than that shown, the vane 80 can be raised to a position such that a small portion of the width of the shelves 47 will discharge grain to the left of said vane. The vane thus serves to guide the grain into the proper hopper 72 or 73 as the case may be.

The operation of the device, it is believed, will be understood from the description given above. However, the same will be briefly reviewed here. Grain is fed from the feeding device 51 through the spouts 57 into the boxes 58, 59 and 60. It is then shaken with a rotary oscillating motion upon the shelves 47 and, due to the arrangement of the zig-zag shoulders on the shelf-like members 47, the heavier grains will travel diagonally toward the corner 66 of each of the shelves 47 and the lighter particles, or those having a lesser density, will travel diagonally toward the corners opposite the corners 66 at the discharge end of the device, the grains traveling toward the corners 66 emptying into the hopper 73 and from said hopper 73 into the hopper

or spout 75 and those traveling toward the lower corners at the discharge end of the device will enter the hopper or spout 72 and from said spout or hopper 72 will drop into the hopper or spout 74 thus separating the grain of two different densities or other particles of two different densities into two well defined groups.

Any suitable means may be provided for bracing the framework, such as the diagonally extending braces shown in Figs. 1 and 3, the braces shown in Fig. 1 comprising the diagonal portions 87, secured to the upright members 11, and the intermediate portion 88, secured to the base 10. The brace shown in Fig. 3 is substantially the same in construction, comprising the diagonally extending portions 89 and the portion 90 lying flat against the base 10, the diagonally extending portions 89 being secured at the opposite ends thereof to the uprights 11. 85

Any suitable lubricating means may be provided for the bearings 42, the lubrication devices 91 shown in Fig. 3 being one form of lubricating means that may be used.

Having thus described my invention, what I desire to claim and secure by U. S. Letters Patent is:

1. In a device of the character described, a shelf-like member means for feeding particles to be sorted thereon at one end thereof, means for oscillating said member, and formations on said shelf-like member facing only toward one side and the opposite end thereof for moving the particles engaging said formations toward one side and the opposite end of said shelf-like member. 95

2. In a device of the character described, a shelf-like member adapted to receive particles to be sorted thereon, means for moving said member with a rotary shaking motion, and projections on said member facing only toward one side and the opposite end thereof engaged by certain of said particles the particles engaging with any of said projections all moving in substantially the same 110 direction.

3. In a device of the character described, a shelf-like member adapted to receive particles of different densities thereon, means for shaking said member, and formations on said shelf-like member with which the heavier of said particles engage to move said particles in one direction, said shelf-like member being inclined so that the lighter of said particles move over said formations in a direction at an acute angle to that of said heavier particles upon shaking said member. 115

4. In a device of the character described, a shelf-like member adapted to receive particles of different densities thereon, means for shaking said member with a rotary shaking motion of small radius of rotation, and 125

formations on said shelf-like member with which the heavier of said particles engage to move said particles in one direction, said shelf-like member being inclined so that the 5 lighter of said particles move in a different direction than said heavier particles upon shaking said member.

5. In a separating device, an imperforate inclined shelf-like member, zig-zag shoulders on said member facing only toward one side and one end thereof and means for shaking said member with a rotary shaking movement of small radius.

6. In a separating device, an imperforate 15 inclined shelf-like member, zig-zag shoulders on said member, and means for shaking said member with a rotary shaking movement of small radius, said shoulders all facing the higher side of said shelf-like member.

7. In a separating device, an inclined shelf-like member having a plurality of inclined faces extending lengthwise thereof, and shoulders separating said faces, said 25 shoulders having alternating walls extending at oblique angles to the longitudinal axis of said member and all facing the higher side of said shelf-like member, and means for shaking said member with a rotary shaking 30 movement.

8. In a grain separator, a plurality of imperforate superposed shelves, means for feeding grain on said shelves at one end thereof, zig-zag shoulders on said shelves, means for 35 imparting a rotary shaking movement to said shelves and means at the other end of said shelves for receiving said grain.

9. In a grain separator, a plurality of imperforate superposed shelves, means for feeding grain on said shelves at one end thereof, zig-zag shoulders on said shelves, means for imparting a rotary shaking movement to said shelves and means at the other end of said shelves for receiving said grain, 45 said means comprising a pair of grain receiving members arranged side by side transversely of said shelves.

10. In a grain separator, a plurality of imperforate superposed transversely inclined 50 shelves, means for feeding grain on said shelves at one end thereof, zig-zag shoulders on said shelves, means for imparting a rotary shaking movement to said shelves and means at the other end of said shelves for receiving said grain.

11. In a grain separator, a plurality of imperforate superposed shelves, means for feeding grain on said shelves at one end thereof, longitudinally extending, substantially parallel zig-zag shoulders on said shelves, means for imparting a rotary shaking movement to said shelves and means at the other end of said shelves for receiving said grain.

65 12. In a grain separator, a plurality of

superposed transversely inclined shelves, means for feeding grain on said shelves at one end thereof, longitudinally extending, substantially parallel zig-zag shoulders on said shelves, means for imparting a rotary 70 shaking movement to said shelves and means at the other end of said shelves for receiving said grain, said shoulders facing the higher sides of said shelves, whereby the lighter grains move toward one corner of said shelves at the discharge end thereof and the heavier grains move toward the other corner of said shelves at said discharge end.

13. In a grain separator, a plurality of imperforate superposed transversely and 80 longitudinally inclined shelves, means for feeding grain on said shelves at one end thereof, zig-zag shoulders on said shelves, means for imparting a rotary shaking movement to said shelves and means at the other 85 end of said shelves for receiving said grain.

14. In a grain separating device, a framework, a plurality of imperforate substantially parallel inclined superposed shelves, means for suspending said shelves from said framework and means for imparting a 90 rotary shaking motion to said shelves.

15. In a grain separating device, a framework, a plurality of substantially parallel inclined superposed shelves, means for suspending said shelves from said framework and means for imparting a rotary shaking motion to said shelves, said means comprising a member mounted for rotation on said suspending means, said member being overbalanced always on the same side of its axis 100 the axis of said member being fixed with respect to said shelves.

16. In a grain separating device, a framework, a plurality of substantially parallel 105 inclined superposed shelves, means for suspending said shelves from said framework and means for imparting a rotary shaking motion to said shelves, said means comprising a member mounted for rotation about a vertical axis on said suspending means, the center of gravity of said member being always eccentric to said axis the axis of said member being fixed with respect to said shelves.

17. In a grain separator, a plurality of superposed shelves, means for feeding grain on said shelves at one end thereof, zig-zag shoulders on said shelves, means for imparting a rotary shaking movement to said shelves, means at the other end of said shelves for receiving said grain, said means comprising a pair of grain receiving members arranged side by side transversely of said shelves, and means for directing the grain discharged from said shelves into said members.

18. In a grain separator, a plurality of superposed shelves, means for feeding grain on said shelves at one end thereof, zig-zag 130

shoulders on said shelves, means for imparting a rotary shaking movement to said shelves, means at the other end of said shelves for receiving said grain, said means comprising a pair of grain receiving members arranged side by side transversely of said shelves, and means for directing the grain discharged from said shelves into said members, said means being adjustable to 10 vary the point of separation of said grain transversely of said shelves at the discharge end thereof.

19. In a grain separator, a plurality of superposed shelves, means for feeding grain 15 on said shelves at one end thereof, zig-zag shoulders on said shelves, means for imparting a rotary shaking movement to said shelves, means at the other end of said shelves for receiving said grain, said means comprising a pair of grain receiving members arranged side by side transversely of said shelves, and means for directing the grain discharged from said shelves into said members, comprising an adjustable vane between said grain receiving members.

20. In a grain separating device, a fixed framework, a suspended framework hung from said fixed framework and movable substantially in a horizontal plane, a plurality of superposed parallel inclined shelves having shoulders thereon on said last mentioned framework and means for imparting a rotary shaking motion to said suspended framework and said shelves, said means comprising a member rotatably mounted on said suspended framework and means on said fixed framework connected to said member for rotating it.

21. In a grain separating device, a fixed framework, a suspended framework hung from said fixed framework and movable substantially in a horizontal plane, a plurality of superposed shelves on said last mentioned framework and means for imparting a rotary shaking motion to said suspended framework and said shelves, said shelves being transversely inclined and having formations on the upper faces thereof, whereby lighter and heavier grain is moved on 50 different diagonals toward opposite corners of said shelves.

22. In a device of the character described, a shelf-like member adapted to receive particles to be sorted thereon near one end 55 thereof, means for moving said member with a rotary shaking motion, and projec-

tions on said member facing only toward one side and the opposite end thereof engaged by certain of said particles by the action of gravity, the particles engaging with any of said projections all moving in substantially the same direction.

23. In a device of the character described, a shelf-like member, means for feeding particles to be sorted on one end thereof, said member being inclined toward the other end and one side thereof, means for shaking said member with a rotary movement and formations on said member engaging the denser of said particles to move the same toward the other side and the last mentioned end of said shelf.

24. In a device of the character described, a shelf-like member, means for feeding particles to be sorted on one end thereof, said member being inclined toward the other end and one side thereof, means for shaking said member with a rotary movement and formations on said member engaging the denser of said particles to move the same toward the other side and the lower end of said shelf.

25. In a device of the character described, a shelf-like member, means for feeding particles to be sorted on one end thereof, said member being inclined toward the other end and one side thereof, means for shaking said member with a rotary movement and formations on said member engaging the denser of said particles to move the same toward the other side and lower end of said shelf, the transverse movement of said particles due to said formations being toward the higher side of said shelf-like member.

26. In a device of the character described, a shelf-like member, means for feeding particles to be sorted on one end thereof, means for rotatively shaking said member, said shelf-like member being inclined to direct particles thereon toward one corner at the other end thereof by gravity upon oscillation thereof, and formations on said shelf-like member facing only toward one side and the opposite end thereof for directing particles thereon toward the other corner thereof at said last mentioned end upon oscillation thereof.

In witness whereof, I hereunto subscribe my name this 5 day of July A. D., 1923.

LESTER L. LADD.
